(57) CLAIM

The ornamental design for a top band for an article of hosiery, as shown and described.

DESCRIPTION

FIG. 1 is a perspective view of a top band for an article of hosiery showing our new design;

FIG. 2 is a side elevational view thereof;

FIG. 3 is a rear perspective view thereof; and,

FIG. 4 is a sectional view taken along line 4—4 of FIG. 1. The broken lines shown herein are for illustrative purposes only and form no part of the claimed design.

1 Claim, 3 Drawing Sheets
